US00D908643S

(12) **United States Design Patent** (10) Patent No.: **US D908,643 S**
(45) Date of Patent: ** *Jan. 26, 2021

(54) **CONTROL DEVICE**

- (71) Applicant: **Lutron Technology Company LLC**,
Coopersburg, PA (US)
- (72) Inventors: **Chris Dimberg**, Easton, PA (US);
Susan Hakkarainen, Doylestown, PA
(US); **Jason C. Killo**, Emmaus, PA
(US); **Brad Michael Kreschollek**,
Bethlehem, PA (US); **Noel Mayo**,
Philadelphia, PA (US); **Matthew Philip
McDonald**, Phoenixville, PA (US)
- (73) Assignee: **Lutron Technology Company LLC**,
Coopersburg, PA (US)
- (*) Notice: This patent is subject to a terminal disclaimer.
- (**) Term: **15 Years**
- (21) Appl. No.: **29/699,451**
- (22) Filed: **Jul. 25, 2019**

Related U.S. Application Data

- (63) Continuation of application No. 29/680,802, filed on
Feb. 20, 2019, now Pat. No. Des. 893,437, which is
a continuation of application No. 29/633,233, filed on
Jan. 12, 2018, now Pat. No. Des. 846,508, which is a
continuation of application No. 29/569,814, filed on
Jun. 30, 2016, now Pat. No. Des. 814,428.

CLAIM

The ornamental design for a control device, as shown and
described.

DESCRIPTION

FIG. 1 is a front view of a control device showing our new
design;

FIG. 2 is a left side view thereof;

FIG. 3 is a right side view thereof;

FIG. 4 is a top view thereof; and,

FIG. 5 is a bottom view thereof.

1 Claim, 1 Drawing Sheet
